UNITED STATES PATENT OFFICE.

MORRIS FATMAN, OF NEW YORK, N. Y.

DESIGN FOR A CLOTH FOR CLOAKING, &c.

SPECIFICATION forming part of Design No. 19,158, dated June 18, 1889.

Application filed May 24, 1889. Serial No. 312,003. Term of patent 3½ years.

To all whom it may concern:

Be it known that I, MORRIS FATMAN, a citizen of the United States, residing at New York city, in the county of New York and 5 State of New York, have invented and produced a new and original Design for Cloakings and similar Goods; and I do declare the following to be a full, clear, and exact description of the same, reference being had to 10 the accompanying drawing, forming a part thereof, in which a face view of the cloth is represented.

The leading feature of my design consists in the representation of a series of rosette-like figures composed of circular or substantially circular members collected into groups of four and arranged in line with each other, the space between the several groups of circular members being filled in by scroll-like 15 members, the whole together—*i. e.*, the groups of circular members and the scroll-like members connecting them—forming bands running across the face of the cloth. The sev-

eral bands are separated by a suitable space, whereby the said bands are rendered more 25 conspicuous. The width of the space is immaterial.

In the drawing A, are the circular or substantially circular members formed into the general conformation of rosettes, as shown. 30 B is the scroll-work. C are the spaces between the bands, formed by the rosettes and scroll-work.

I claim—

The design for cloth herein shown and described, the same comprising a series of rosettes connected by scroll-work arranged in the form of bands and separated from one another by a space on the cloth, substantially as set forth. 35

In testimony whereof I affix my signature in presence of two witnesses.

MORRIS FATMAN.
